UNITED STATES PATENT OFFICE.

CHARLES W. IBACH, OF TACOMA, WASHINGTON.

AUTOMATIC LOCOMOTIVE-TANK-VALVE RELEASE.

1,270,760.

Specification of Letters Patent. Patented June 25, 1918.

Application filed March 30, 1916. Serial No. 87,750.

To all whom it may concern:

Be it known that I, CHARLES W. IBACH, a citizen of the United States, residing at Tacoma, in the county of Pierce, State of

5 Washington, have invented certain new and useful Improvements in Automatic Locomotive-Tank-Valve Releases, of which the following is a specification.

This invention relates to devices for controlling the valve in the tank of a locomotive, and has for its objects to provide such a device which will hold the valve open when it is desired to have the valve open and which will allow the valve to close 15 when it is desired to close said valve; also a device which will automatically allow said valve to close if the draw-bar between the locomotive and its tank should break, thereby preventing the water, oil, or other fluid 20 in the tank from escaping freely therefrom in case of an accident.

I attain these and other objects by the devices, mechanisms, and arrangements illustrated in the accompanying drawings, in 25 which:

Figure 1, is a side elevation, partly in section, showing my device in use;

Fig. 2 is a perspective view thereof showing it in the position occupied thereby when 30 the valve is open; and Fig. 3 is a similar view showing it in the position occupied thereby when the valve is closed, and also showing the connection to the locomotive being broken as when the draw-bar has 35 parted.

Similar numerals of reference refer to similar parts throughout the several views.

When, in a railroad accident, the draw-bar between the engine and the tank has 40 parted, the pipe connections are broken under the strain and the contents of the tanks immediately flow freely through the said broken pipes. In the case of an oil-burning locomotive this is very dangerous as well as 45 expensive, since this oil is spread on the ground and may readily be ignited thus possibly destroying the train and doing great damage otherwise. In order that this outflow may be automatically stopped as 50 soon as the draw-bar between the engine and tank has parted, I have devised the following described mechanism.

The tank car 1 is attached to the locomotive 2 by means of a draw-bar 3. A valve seat 4 is mounted in the bottom of the tank and a valve 5 is mounted above said seat and

is adapted to close it. A strong spring 6 presses said valve 5 downward on said seat to close the passage. A suitable pipe 7 leads from the seat 4 to the locomotive. 60

The valve 5 is held open, against the action of the spring 6, by a rod 8 which passes through the top of the tank and which is connected to the valve stem by means of a chain or cable 9. The rod 8 is secured in a 65 head 10, which is pivoted in the two arms 11 of my holding and releasing device. This consists of a member bent and formed so that when it is holding the valve open (as in Figs. 1 and 2) the two arms 11 are bent 70 slightly back of the vertical so that the line of strain of said rod 8 comes well forward of the lower corners of said arms 11; the arms are bent at their lower corners to form short bases 12, and these are bent upward 75 and toward each other, as at 13, to form a stem 14 which is slightly raised above the tank top; this stem extends to the front edge of the tank and is then bent down at less than a right-angle to form the short extension 15. A notch 16 is made in the lower side of the extension 15 and a spring 17 is secured to the lower side of the part 15 and extends downward to close over the notch 16. 80

A cable or rope 18 is secured to the roof 85 19 of the cab and passes over a pulley 20 and then down and terminates in a link 21. This link 21 is adapted to lie in the notch 16 in the extension 15.

When the device is set for holding the 90 valve open, as shown in Figs. 1 and 2, the strain of the spring 6 bears down through the arms 11 on the bases 12. If, however, the cable 18 is pulled by the fireman, it pulls upward on the extension 15 and turns the 95 whole device on the corners between the said bases 12 and arms 11 so that the strain of the spring 6 will then pass outside of said corners thus allowing it to turn. This releases the rod 8, cable 9 and valve 5 so that 100 the spring 6 will force the valve down on the seat 4. If the draw-bar 3 should be broken, the locomotive will move away from the tank and the cable 18 will then pull on the extension 15 and turn the device as before described, thus automatically closing 105 down said valve 5.

Having described my invention, what I claim is:

1. In combination, a valve, means tending 110 to close the valve, a device operatively connected to said valve and adapted in one posi-

tion of adjustment to hold the valve open and in another position to permit the said means to close the valve, a spring secured to said device, and a cable releasably secured by said spring to said device and adapted on actuation to move said device from the first named to the second position to effect closure of the valve.

2. In combination, a valve, means acting 10 to close said valve, a holding and releasing device operatively connected to said valve and comprising a stem and an arm projecting substantially at a right angle from one

end of the stem, the other end of said stem 15 being offset in a direction opposite to that in which said arm extends, said arm adapted in one adjustment of said device to hold the valve open, and in another adjustment to permit the valve to close under action of 20 said closing means, a spring carried by the offset end of said stem, and a cable releasably secured by said spring to said device and adapted to actuate said device to effect a closure of the valve.

CHARLES W. IBACH.
